UNITED STATES PATENT OFFICE.

THOMAS ELLIOTT, OF CINCINNATI, OHIO, ASSIGNOR TO THE CINCINNATI CAR COMPANY, OF CINCINNATI, OHIO, A CORPORATION OF OHIO.

STEEL CAR CONSTRUCTION.

1,375,786.

Specification of Letters Patent. Patented Apr. 26, 1921.

Application filed March 13, 1919. Serial No. 282,338.

To all whom it may concern:

Be it known that I, THOMAS ELLIOTT, a citizen of the United States, residing at Cincinnati, in the county of Hamilton and State of Ohio, have invented certain new and useful Improvements in Steel Car Constructions, of which the following is a specification, reference being had therein to the accompanying drawings:

10 This invention relates to improvements in steel car construction and has for its particular object to provide certain improved features pertaining to details of construction of electric railway cars.

15 An object of the invention is to provide an improved construction of the sides and roof of an electric railway passenger car whereby a simple, substantial construction is obtained and whereby the roof of the car 20 constitutes a separate unit of the car body, thus facilitating and cheapening the assembling of the car body structure.

25 A further object is to provide a construction which will permit of ready access to and removal of the different parts, thus facilitating and cheapening car maintenance.

30 The improvements relate specifically to the details of a detachable roof having novel means for securing the roof covering to the supporting arches, and the arches to the side posts.

35 The improvements further relate to details of the sash construction and arrangement, having particular reference to an improved water shed or drip; also to a novel arrangement for adapting belt plates to the side posts and securing the posts to the side sills.

40 The improvements taken as a whole result in correcting various faults of car designing which give rise to certain objections relative to inaccessibility of parts, and features of impracticable construction which 45 have proved unsatisfactory in practical use.

In the accompanying drawings:

Figure 1 is a vertical section through the side of the car body including a portion of the roof structure;

50 Fig. 2 is a detailed side elevation of one of the side posts, showing the manner of cutting away a portion of the post and reinforcing the same to provide for the convenient assembling of the belt rails to the body of the car;

Fig. 3 is a detail cross section of one of the roof-supporting arches taken on the line 3—3 of Fig. 1;

Fig. 4 is a detail cross section taken on the line 4—4 of Fig. 1, showing the manner of securing the roof arches to the side posts and including the inner lining of the roof or car ceiling.

Fig. 5 is a detail cross section taken on the line 5—5 of Fig. 1 and showing the manner of securing the letter board or eaves plate to the side posts;

Fig. 6 is a detail cross section taken on the line 6—6 of Fig. 1, and showing the relation of the upper continuous sash to the side posts;

Fig. 7 is a detail cross section of the lower operable sash construction taken on the line 7—7 of Fig. 1;

Fig. 8 is a detail cross section on the line 8—8 of Fig. 1 showing the manner of reinforcing the side post at the point where it is intersected by the belt rail.

Referring to the drawings, 1 is the inverted angle side sill to which the side posts 2 are rigidly secured, as by rivets 3. The posts 2 are T-shaped in cross section and extend upwardly from the side sills to the roof of the car, their upper portion being offset outwardly, as at 4, for a purpose which will presently be explained, their upper ends being inclined inwardly at an angle, as at 5, to form a convenient connection with the roof-supporting arches, the posts and arches being secured together in any suitable manner, preferably as here shown by bolt, 6.

At a point adjacent the belt rail 7 and the lower edge of the lower sash a portion of the T-posts is cut away, best shown in Fig. 2 of the drawings, permitting the belt rail to intersect the posts, as at 8, thus forming a neat compact structure, convenient to assemble and having ample strength for its intended purposes of serving as a lateral brace and support for the girder plate and as a sill water shed and flashing for the lower sash. To compensate for the cutaway portion of the T-posts a reinforcing plate 9 is welded to the inwardly projecting flange of the posts, thus restoring the same to their normal strength and rigidity.

Referring to the off-set portion 4 of the T-posts, it will be observed that an arch 10 is formed at the juncture of the posts at this point with the letter-board 11, adapted to

inclose the upper edge of the top rail 12 of the upper continuous sash, the lower edge of the letter board overlapping the top rail in a manner and to an extent to form a deep, 5 close fitting joint which serves to effectually prevent ingress of wind, dust and water to the interior of the car and to hold the sash securely in place.

The offset feature of the T posts further 10 provides for convenient and effective riveting of the letter boards to the posts, as shown at 13, a distinct advantage being gained by the offset post in bringing the inner heads of the rivets out of the plane of 15 upward movement of the lower sash, thus enabling a substantial job of riveting and preventing interference and cutting of the sash when it is raised. To avoid interference with the sash it has been common practice to use flat head rivets and countersunk 20 holes to bring the rivet heads flush with the inner surface of the T-posts, but this method of riveting is expensive and generally unsatisfactory.

25 The manner of securing the belt rail to the T-posts and girder plate provides a substantial support or sill for the lower sash, and permits using a belt rail of sufficient weight to provide an effective longitudinal 30 bracing of the car frame. Thus strength and stability are provided at a vital point of the car structure without introducing excessive weight, the substantial construction of the belt rail and T-posts permitting the use 35 of a lighter girder plate to inclose the lower portion of the car body. There being no great stress upon the girder plate a very light gage of metal may be used.

It will be apparent that the T-posts are 40 readily detachable and may be removed singly by cutting the rivets at the top and bottom and unbolting the post from the roof arch. Thus in the maintenance of the car in event of a collision indenting the side of 45 the car, which is a very common experience, the bent posts can readily be removed, straightened and replaced with the minimum of time and labor. While as here shown the side posts are T-shaped in cross section, their 50 shape is not essential to the purposes of the invention and posts of different shapes in cross section may be used.

An important feature of the present invention consists in the improved construction 55 and manner of supporting the detachable roof. As here shown the roof constitutes a complete unit separable as a whole from the car body. The construction consists of the rectangular-shaped or U-shaped 60 channels 14 which constitute supporting arches for the roof covering 15. The ends of the arches, as shown in Figs. 1 and 4, are bolted to the inwardly inclined ends of the T-posts on opposite sides of the car, thus 65 making the two posts and arch of each set

one supporting structure. The ends of the arches are preferably provided with integral flanges 14¹ extending at right angles to the channels and serving as a means for securing the arches to a wood strip 18 extending longitudinally of the car, and constituting 70 the roof frame and hood bow.

As here shown the channels of the supporting arches are preferably provided with a nailing strip 16, of wood or other suitable 75 material, for securing the roof covering to the arches.

As shown in Fig. 4 a lining or ceiling 17 of any suitable material may be secured to the underside of the arches and give finish 80 to the interior of the car.

As shown in Fig. 1, the edge of the roof projects somewhat over the side of the car, the overhanging edge being supported by the longitudinal strip 18. The overhanging 85 projection of the roof is sufficient to normally shed water from the roof free of the letter-board and the upper and lower sash, thus acting to prevent the same becoming soiled from roof drainage.

From the foregoing detailed description it will be apparent that the improvements of my invention consist essentially in the novel features of construction and arrangement here shown, whereby the roof structure 90 is made a separate detachable unit; the detachable feature of the side posts, the method of reinforcing the posts and intersecting the same with the belt rails; and off-setting the posts at their upper ends to seat and protect 95 the upper sash and to provide satisfactory riveting conditions to secure the letter-board thereto; the novel arrangement of inserting a nailing strip in the channel arches; and the projecting roof to protect the letter-board and sides of the car from roof 100 drainage.

These improvements relate to important features of car construction and go directly to the cost of production and maintenance; 110 convenience of assembling the car body; ready accessibility of parts for making repairs or replacements; and the general improvement tending toward more substantial and more practicable car construction.

Having thus fully described my invention, what I claim as new and desire to secure by Letters Patent, is:—

1. In a railway car, the combination, with a roof adapted as an independent unit to 110 be detachably secured to the completed car body and comprising a channeled arch having a nailing strip therein to which the roof covering is secured; a side post detachably secured to said arch and supporting the arch 120 and roof.

2. In a railway car, the combination, with a roof adapted as an independent unit to 125 be detachably secured to the completed car body and comprising a channeled arch sub- 130

stantially rectangular in cross section and having a wood strip inserted in said channel to which the roof covering may be secured, and a side post detachably secured to said arch and supporting the arch and roof.

3. In a railway car, the combination, with a roof adapted as an independent unit to be detachably secured to the completed car body and comprising a channeled arch having a suitable material in said channel to which the roof covering may be secured, and a side post detachably secured to said arch and supporting the arch and roof.

4. In a railway car, the combination, with a roof adapted as an independent unit to be detachably secured to the completed car body and comprising a channeled arch supporting said roof and having a wood strip in said channel whereby the roof covering is secured to said arch, and a side post detachably secured to said arch and supporting the arch and roof.

5. In a railway car, the combination, with a roof adapted as an independent unit to be detachably secured to the completed car body and comprising a channeled arch supporting said roof and having suitable material in said channel whereby the roof covering may be secured to said arch.

6. In a railway car, the combination, with a roof adapted as an independent unit to be detachably secured to the completed car body and comprising a channeled arch supporting said roof and having suitable material in said channel whereby the roof covering may be secured to said arch, and means for securing an inner covering for said arch and roof.

7. In a railway car, the combination, with a roof adapted as an independent unit to be detachably secured to the completed car body and comprising a supporting arch and means for securing the roof covering to said arch; and a T-post supporting the roof and having an inclined end detachably secured to said arch.

8. In a railway car, the combination, with a roof adapted as an independent unit to be detachably secured to the completed car body and comprising a supporting arch and means for securing the roof covering to said arch; and a post supporting the roof and having an inclined end detachably secured to said arch.

55 9. In a railway car, the combination, with a roof adapted as an independent unit to be detachably secured to the completed car body and a post having an inwardly inclined end detachably secured to and supporting said roof.

60 10. In a railway car, the combination, with a detachable roof, a post having an inwardly inclined end detachably secured to and supporting said roof, and a letter-board extending longitudinally of the car and se-

cured to the inclined end of said post and the roof.

11. In a railway car, the combination, with a detachable roof, a post having an off-set portion and an inwardly inclined end detachably secured to and supporting said roof, and a letter-board extending longitudinally of the car and secured to the off-set portion and inclined end of said post.

12. In a railway car, the combination, with a detachable roof, a post having an off-set portion and an inwardly inclined end detachably secured to and supporting said roof, and a letter-board extending longitudinally of the car and secured to the off-set portion of said post.

13. In a railway car, the combination, with a detachable roof, a post having an outwardly off-set portion and an inwardly inclined end detachably secured to and supporting said roof, and a letter-board extending longitudinally of the car and secured to the off-set portion of said post.

14. In a railway car, the combination, with a detachable roof having a laterally projecting edge, a post having an outwardly off-set portion and an inwardly inclined end detachably secured to and supporting said roof, a letter-board extending longitudinally of the car and secured to the off-set portion of said post, the projecting edge of the roof 95 extending over the letter board.

15. In a railway car, the combination, with a detachable roof having a longitudinal strip and a laterally projecting edge, a post having an outwardly off-set portion and an inwardly inclined end detachably secured to and supporting said roof, a letter-board extending longitudinally of the car and secured to the off-set portion of said post, said 100 strip and the projecting edge of the roof extending beyond the vertical plane of the letter-board.

16. In a railway car, the combination, with a side post having an upper off-set portion 110 forming an outwardly projecting shoulder, an upper continuous sash having its upper edge resting against said shoulder, a letter-board secured to the off-set portion of said post and having its lower edge projecting 115 outwardly and downwardly over the edge of said sash.

17. In a railway car, the combination, with a side post having an upper off-set portion forming an outwardly projecting shoulder, 120 an upper sash having its upper edge resting against said shoulder, a letter-board secured to the off-set portion of said post and having its lower edge projecting downwardly over the edge of said sash.

18. In a railway car, the combination, with an operable sash, a post secured to the side sill of the car and having a cut-away reinforced portion, a belt rail extending longitudinally of the car and having an inwardly 130

inclined portion projecting into the cut-away portion of said post and forming a shoulder upon which said sash rests.

19. A railway car comprising a sash, a side post secured to the sill of the car and acting as a guide for the sash, a belt rail extending longitudinally of the car and having an inwardly inclined portion intersecting said post and forming a sill for said

10 sash.

20. A railway car comprising a T post secured to the side sill of the car, the post having a reinforced cut away portion, a belt

15 rail extending longitudinally of the car and having an inwardly projecting portion intersecting said post at the cut away portion thereof.

21. A railway car comprising a post secured to the side sill of the car, the post having a cut away portion, a belt rail extending longitudinally of the car and having an inwardly extending portion intersecting said post at the cut away portion thereof.

In testimony whereof, I affix my signature.

THOMAS ELLIOTT.
